UNITED STATES PATENT OFFICE

FRANK W. SEVERIN, OF CHICAGO, ILLINOIS, ASSIGNOR TO VENN-SEVERIN MACHINE CO., OF CHICAGO, ILLINOIS, A CORPORATION OF ILLINOIS

ENGINE

Application filed August 23, 1926. Serial No. 130,841.

The invention relates to engines of that type in which crank-shafts are used.

One object of the invention is to provide a bearing structure which facilitates placement and removal of the units in which the shaft rotates and which are subjected to wear and which permits replacement of such units without the necessity of removing the crank-shaft from the crank-case or separating the sections of the crank-shaft.

Another object of the invention is to provide an improved crank-shaft bearing which may be readily placed into position and removed for repair or replacement, and which is adapted for engagement with a seal-ring in a crank-case in which air is compressed for transfer to the working-cylinder or cylinders.

Other objects of the invention will appear from the specification.

The invention consists in the several novel features hereinafter set forth and more particularly defined by claims at the conclusion hereof.

In the drawings: Fig. 1 is a longitudinal section of an engine embodying the invention, one of the bearings being shown in elevation. Fig. 1^a is a section on an enlarged scale of one of the seal-rings and its contiguous bearing section. Fig. 1^b is a side elevation of said ring. Fig. 2 is a section on line 2—2 of Fig. 1. Fig. 3 is a section through one of the crank-shaft bearings taken on line 3—3 of Fig. 1. Fig. 4 is a section showing two of the air inlet valves mounted in the crank-case. Fig. 5 is a perspective of a portion of one of the bearing-beds formed in the lower section of the crank-case and a portion of one of the cross-walls. Fig. 6 is a perspective of the upper, and Fig. 6^a a perspective of the lower, of a pair of units forming one section of the removable bearing for the crank-shaft. Fig. 7 is a perspective of one of the retaining caps for the bearing sections. Fig. 8 is a perspective of one of the removable spacers which is placed between the sections of a bearing. Fig. 9 is a view, partly in plan and partly in section of one of the bearings.

The invention is exemplified in an internal combustion engine of the two cycle type

which comprises a crank-case composed of a base-section *a* and an upper section *a'* which have their meeting faces in the horizontal plane of the axis of the crank-shaft; working cylinders *c*, *c'* mounted on the section *a'*; a 55 crank-shaft *b* extending longitudinally through the crank-case and held between the sections thereof and provided with a crank *b'* for each cylinder; a reciprocable piston *d* in each cylinder and pitmen *d'* connecting the pistons and the cranks. Adjacent either end of each crank *b'*, the crank-case section *a'* is integrally formed with a septum or wall *a²* and the section *a* with a wall or septum *a³*, vertically aligned with the wall *a²*, to form 60 an enclosure or compression chamber for air which is transferred to the combustion end of the cylinder, as well understood in the art. The crank-case section *a* comprises end walls *a⁴*, and the section *a'* comprises end walls *a⁵* 65 vertically aligned with the walls *a⁴*.

Between the walls *a³*, which are disposed between the cranks *b'* and between the end walls *a⁴* and the walls *a⁵* adjacent the outer ends of the cranks, are formed semi-cylindrical walls which form beds *a⁶*, each with a semi-cylindrical inner periphery *a⁷* for one of the removable crank-shaft bearings. There is one bed *a⁶* between the cranks and one adjacent each of its ends. Each wall *a³* 75 and *a⁴* is formed with a semi-cylindrical opening *a⁸* which joins a periphery *a⁷* to form cylindrical seats *a⁹* in which the ends of the bearings are held and fit. There is a bearing 80 in each of the beds and these are alike in construction so that a detail description of one applies to all.

Each crank-shaft bearing comprises a pair of separate ring-like sections and each section 85 comprises a lower semi-cylindrical unit *d*, 90 the inner periphery of which is lined with babbitt or anti-friction metal, and a complementary upper semi-cylindrical unit *d'* which is similarly lined with babbitt as at *d¹*. When the upper and lower units are 95 together, they form a completely cylindrical bearing-section for the shaft. The outer end of each section has a cylindrical outer periphery *d²* which conforms to the bore of and fits snugly in one of the cylindrical seats *a⁹*, 100

so that the sections may be slipped endwise and while positioned around the crank-shaft into said seats. The entire outer face of each lower unit d is cylindrical, conformably to the inner periphery a^7 of bed a^6 , so that it may be, when detached from its upper unit, rotated into and out of position on the bed and around the shaft, as well as moved longitudinally into and out of seat a^{40} . The central portion of each unit d^3 is cut away or channelled, as at d^5 , to avoid excess of metal and is formed with an oil pocket d^{30} . The upper units are each provided with laterally projecting integral lugs d^9 which are adapted to project over and abut against the top face of wall a^6 to hold the sections against rotation in the bed. Screws d^{20} are adapted to pass through said lugs and into threaded holes d^{15} in unit d to secure the units of a section together.

The outer end of each section which enters a seat a^{40} is provided with an annular groove d^{10} in its outer periphery to hold a ring of packing d^{11} to form a seal between the crank-case and the bearings. The bearing-sections are held and spaced apart by a pair of arcuate blocks d^{12} which are formed to lie between the circular shoulders d^{13} on the contiguous ends of the sections and the periphery a^7 of the bed a^6 . These blocks are shaped so they may be rotated into and out of place. The upper units are clamped into position relatively to the bed and against upward movement by a cap e which comprises a semi-cylindrical portion e' adapted to fit over the outer periphery of the inner end of the units d^3 and lugs e^2 which project laterally over lugs a^9 which are cast integrally with the bed a^6 , and are provided with holes e^3 for bolts e^4 which removably clamp the cap to the bed to secure the sections in their seats a^{40} . The inner periphery of the cap e is provided with a groove e^5 , so that the cap will longitudinally interlock with the blocks d^{12} .

In engines in which a compression-chamber is formed in the crank-case, it is important to prevent leakage from the chamber and through the shaft-bearings, and one object of the invention is to provide a removable bearing which is adapted for use with a seal-ring employed for this purpose. At the end of each of the crank-shaft bearings, there is provided a seal-ring f which is formed of semi-cylindrical sections secured together by bolts f^{10} , so that it may be assembled around the crank-shaft. Each ring is provided with pins f' which extend into sockets f^2 in a side of one of the cranks b' or into the fly-wheel, to cause it to be driven with the crank-shaft. Springs f^2 , held in sockets f^3 in the seal-ring, press the ring away from the shaft and against the contiguous end of a shaft-bearing. The outer face f^4 of each seal-ring is flat to engage the end of one of the bearings and to form a closure which will

prevent air from escaping from the crank-chamber between the periphery of the shaft B and the inner periphery of the contiguous removable bearing. The springs serve to press the seal-rings against the bearing ends. The outer periphery f^5 of each ring is formed to lie within the cylindrical seats a^{40} in the aligned walls a^2 and a^3 of the crank-case. A packing ring f^6 is provided in the inner periphery of each seal-ring to prevent leakage between the seal-ring and the shaft. This construction exemplifies one in which the seal-ring bears against the removable bearing in lieu of a wall or septum of the crank-case. As a result, the wear is upon the bearing, which can be readily replaced, in lieu of on the wall or integral part of the crank-case sections. This has been found to be important, because it sometimes occurs that the oil supply fails. When that occurs, the wear will be on the removable bearing-units and the oil ring which can be easily replaced while no injury will result to the walls of the crank-case. When the bearing units are removed, the seal-ring will also be accessible for removal through openings a^{40} . The upper section a' of the crank-case is provided with openings a^{14} which admit air to the spaces between the central pair of walls a^2 and between the end walls a^5 and the adjacent walls a^2 and also provide ready access to the bearings from the outside of the crank-case.

A pair of holes d^{15} are formed in each of the walls a^2 and an air inlet check valve is secured in each of said holes to control the delivery of air into the chamber of the crank-case in which the cranks operate. Each of these valves comprises a grid g ; a valve ring g^2 ; a ring g^3 fitting against the grid and provided with angular intake ducts g^4 and an annular seat g^5 against which the ring valve g^2 is normally pressed by springs g^6 ; a cover g^7 ; and a bolt g^8 which clamps the grid, ring and cover together. Each grid g abuts against one face of a wall a^2 and fits into one of the openings d^{15} . The longitudinally aligned pairs of valves between the central walls a^2 are held in place by a jack-screw g^9 which is interposed between contiguous covers g^7 , is adapted to hold the valve-structures separated and seated against the walls a^2 and is removable to permit the valve-structures to be readily removed when access to the bearings is desired. The air inlet valves in the outer walls a^2 are similarly held in the openings a^{15} by jack-screws g^{10} interposed between the valve-covers g^7 and the end walls a^5 of the upper section of the crank-case.

When the engine has been in operation and a repair or replacement is necessary in the bearing, any one of them may be dismantled and replaced, without separating the crank-case sections or removing the crank-shaft. For example, if the central bearing should become worn and it is desired to re-babbitt it

or replace a unit thereof, it is only necessary to first remove the adjacent air-inlet valves by removing the jack screw g^9 , which will permit the valves to be readily removed as units. Next, the bolts e^4 will be removed to release the cap e , which will then be removed. Next, the blocks d^{12} will be separately rotated around the shaft and out of the bed a^6 and then removed. The sections will then be free to be shifted longitudinally to bring their outer ends out of the seats a^{40} , so that the upper units can be lifted off the shaft when otherwise released. The upper units will then be disconnected from the lower by the removal of screws d^{20} and then removed. The lower units will then be free to be rotated out of the bed a^6 and lifted off the shaft. In replacing or assembling the bearing, the lower units d will be successively inverted and laid on top of the shaft and then rotated around it into the bed. Next, the upper units will be secured thereto by screws d^{20} . The sections will then be shifted outwardly to clip their outer ends into the seats a^{40} . Next, the blocks d^{12} will be inserted between the upper portion of the sections and rotated around the shaft so that they will pass partly into the bed, as shown in Fig. 2. Next, the cap e will be secured over the blocks d^{12} and the units d^3 and then the bearing will be completely assembled.

The invention exemplifies a bearing structure for a crank-shaft which makes it possible to quickly remove and replace any of the shaft bearings without disassembling the shaft from the crank-case or without separating the sections of the crank-case; also one which is adapted for use in connection with a crank-case in which air is compressed for delivery to the working cylinder.

40 The invention is not to be understood as restricted to the details set forth, since these may be modified within the scope of the appended claims, without departing from the spirit and scope of the invention.

45 Having thus described the invention, what I claim as new and desire to secure by Letters Patent, is:

1. A crank shaft bearing for an engine having a crank-case formed of sections and with a cylindrical bearing seat, said bearing comprising upper and lower complementary units provided with outer peripheral portions fitting into said seat, said units being conjointly and longitudinally movable on the shaft into and out of said seat, one of the units being rotatable around the shaft when the other has been removed, and removable means for securing the units against longitudinal movement when the units are in their operative position in the seat.

2. In combination, a crank-case formed of sections, one of which is provided with a bed and the other with a wall, said bed and wall having coacting portions forming a cylindrical bearing seat, a crank-shaft in said case,

and a removable bearing for said shaft comprising upper and lower complementary units provided with outer peripheral portions to fit into said seat, said units being conjointly and longitudinally movable on the shaft into and out of said seat, one of the units being removable by rotation around the shaft when the other has been removed and when both have been shifted longitudinally away from the wall, and removable means for securing the units against longitudinal movement when said units are in their operative position in the seat. 70

3. In combination, a crank-case formed of sections, one of which is provided with a bed and the other with a wall, said bed and wall having coacting portions forming a cylindrical bearing seat, a crank-shaft in said case, and a removable bearing for said shaft comprising upper and lower complementary units provided with outer peripheral portions to fit into said seat, said units being longitudinally movable on the shaft into and out of said seat, one of the units being removable by rotation around the shaft when the other has been removed, and when both have been shifted longitudinally away from the wall, means for securing the units together, and removable means for securing the units against longitudinal movement when the units are 75 80 85 90 95 in their operative position in the seat.

4. In combination, a crank-case formed of sections, one of which is provided with a bed and the other with a wall, said bed and wall having coacting portions forming a cylindrical bearing seat, a crank-shaft in said case, and a removable bearing for said shaft comprising upper and lower complementary units provided with outer peripheral portions to fit into said seat, said units being longitudinally movable on the shaft into and out of said seat, one of the units being removable by rotation around the shaft when the other has been removed and when both have been shifted longitudinally away from the wall, and a removable cap for clamping one of the units to the bed. 100 105 110

5. A bearing structure for the crank shaft of an engine embodying a crank-case provided with a bearing-bed and walls having arcuate portions forming with the bed bearing seats, said structure comprising two pairs of upper and lower complementary units adapted to extend around the shaft and fit into the seats, the units of each pair being conjointly and longitudinally movable on the shaft to permit them to be slipped into and out of their respective seat, one unit of each pair being rotatable around the shaft to permit it to be removed when its complementary unit has been removed, and removable means for securing the units against longitudinal displacement when they are in their operative position in the seats. 115 120 125

6. In combination, a crank-case formed of 130

sections, one of which is provided with a semi-cylindrical bearing-bed and the other with walls approximately aligned with the ends of the bed having arcuate cylindrical portions forming with said bed-ends cylindrical bearing-seats, a crank-shaft, and a removable bearing for the shaft comprising two pairs of upper and lower complementary units adapted to extend around the shaft and fit into seats, the units of each pair being conjointly and longitudinally movable on the shaft to permit them to be slipped into and out of their respective seat, one unit of each pair being rotatable around the shaft to permit it to be turned out of the bed and removed when its complementary unit has been removed, and removable means for securing the units against longitudinal displacement when they are in their operative position in the seats.

7. In combination, a crank-case formed of sections, one of which is provided with a semi-cylindrical bearing-bed and the other with walls approximately aligned with the ends of the bed having arcuate portions forming with said bed-ends cylindrical bearing-seats, a crank-shaft, and a removable bearing for the shaft comprising two pairs of upper and lower complementary units adapted to extend around the shaft and fit into the seats, the units of each pair being conjointly and longitudinally movable on the shaft to permit them to be slipped into and out of their respective seat, one unit of each pair being rotatable around the shaft to permit it to be turned out of the bed and removed when its complementary unit has been removed, means for removably securing the units of each pair together after they have been assembled on the bed, and removable means for securing the units against longitudinal displacement when they are in their operative position in the seats.

8. In combination, a crank-case formed of sections, one of which is provided with a semi-cylindrical bearing-bed and the other with walls approximately aligned with the ends of the bed having arcuate portions forming with said bed-ends cylindrical bearing-seats, a crank-shaft, and a removable bearing for the shaft comprising two pairs of upper and lower complementary units fitting around the shaft and into the seats, said units being longitudinally movable on the shaft to permit them to be slipped into and out of the seats, one unit of each pair being rotatable around the shaft to permit it to be turned out of the bed and removed when its complementary unit has been removed, spacing-means between the pairs of units, and removable means for clamping the units against longitudinal movement when they are in their operative position in the seats.

9. In combination, a crank-case formed of sections, one of which is provided with a semi-cylindrical bearing-bed and the other

with walls approximately aligned with the ends of the bed having arcuate portions forming with said bed-ends cylindrical bearing-seats, a crank-shaft, and a removable bearing for the crank-shaft comprising two pairs of upper and lower complementary units fitting around the shaft into the seats, said units being longitudinally movable on the shaft to permit them to be slipped into and out of the seats, one unit of each pair being rotatable around the shaft to permit it to be turned out of the bed and removed when its complementary unit has been removed, and a cap removably secured to the bed and extended to clamp two units to the bed and against longitudinal displacement relatively to the shaft.

10. In combination, a crank-case formed of sections, one of which is provided with a bearing-bed and the other with walls, the walls and bed having coacting portions forming two cylindrical bearing seats, a crank-shaft, and a bearing structure for the shaft comprising two pairs of upper and lower complementary units fitting around the shaft and into the seats, said units being longitudinally movable on the shaft to permit them to be slipped into and out of the seats, one unit of each pair being rotatable around the shaft to permit it to be removed when its complementary unit has been removed, removable blocks between the pairs of units to space them longitudinally, and removable means to clamp the units in their seats.

11. In combination, a crank-case formed of sections, one of which is provided with a bearing-bed and the other with walls, the walls and bed having coacting portions forming two cylindrical bearing seats, a crank-shaft, and a bearing structure for the shaft comprising two pairs of upper and lower complementary units fitting around the shaft and into the seats, said units being longitudinally movable on the shaft to permit them to be slipped into and out of the seats, one unit of each pair being rotatable around the shaft to permit it to be removed when its complementary unit has been removed, blocks for spacing the pairs of units apart, said blocks being positioned adjacent and between the bed and the shaft, and means to removably clamp the units in the removable seats.

12. In combination, a crank-case formed of sections, one of which is provided with a bearing bed and the other with walls, the walls and bed having coacting portions forming a pair of cylindrical bearing seats, a crank-shaft, and a bearing structure for the shaft comprising two pairs of upper and lower complementary units fitting around the shaft and into the seats, said units being longitudinally movable on the shaft to permit them to be slipped into and out of the seats, one unit of each pair being rotatable around the shaft to permit it to be removed when its complementary unit has been re-

5 moved, blocks between the pairs of units to space them apart, and a cap removably secured to the bed and adapted to clamp one unit of each pair to the bed and to hold the blocks in place.

13. In combination, a crank-case formed of sections, one of which is provided with a bearing-bed and the other with walls, the walls and bed having coacting portions forming a pair of cylindrical bearing seats, a crank-shaft, and a removable bearing for the shaft comprising two pairs of upper and lower complementary units fitting around the shaft and into the seats, said units being longitudinally movable on the shaft to permit them to be slipped into and out of the seats, screws for removably securing the units of each pair together, one unit of each pair being rotatable around the shaft to permit it to be removed when its complementary unit has been removed, the upper units having lugs to engage the top of the bed, and means for clamping the units to the bed.

14. In combination, a crank-case formed of sections, one of which is provided with a bearing-bed and the other with walls, the walls and bed having coacting portions forming a pair of cylindrical bearing seats, a crank-shaft, and a removable bearing for the crank-shaft comprising two pairs of upper and lower complementary units fitting around the shaft and into the seats, said units being longitudinally movable on the shaft to permit them to be slipped into and out of the seats, screws for removably securing the units of each pair together, one unit of each pair being rotatable around the shaft to permit it to be removed when its complementary unit has been removed, the upper units having lugs to engage the top of the bed, and a cap removably secured to the bed and adapted to clamp one unit of each pair to the bed.

15. In combination, a crank-case formed of sections one of which is provided with a bearing bed and the other with walls, the walls and bed having coacting portions forming a pair of cylindrical bearing seats, a crank-shaft, and a removable bearing for the crank-shaft comprising two pairs of upper and lower complementary units fitting around the shaft and into the seats, said units being longitudinally movable on the shaft to permit them to be slipped into and out of the seats, screws for removably securing the units of each pair together, one unit of each pair being rotatable around the shaft to permit it to be removed when its complementary unit has been removed, the upper units having lugs to engage the top of the bed, spacing blocks between the pairs of units, and a removable cap for clamping one unit of each pair to the bed and extending over the blocks to hold them in place.

16. In combination, a crank-case provided with a wall member having a cylindrical

opening therein forming a cylindrical bearing-seat, a crank-shaft, a bearing for the crank-shaft comprising a pair of complementary units fitting around the shaft and in the seat, said units being longitudinally movable on the shaft to permit them to be slipped into and out of the seat, means for holding the units in the seat, and a seal-ring rotatable with the shaft and having a side pressed against one end of the bearing-units.

17. In combination, a crank-case formed of sections provided with aligned transverse walls, said walls having complementary arcuate openings forming a cylindrical bearing-seat, a crank-shaft, a bearing for the shaft removably held in said seat and longitudinally movable to permit it to be slipped into and out of the seat, and a seal-ring rotatable with the shaft and having a side pressed against one end of the bearing-units.

18. In combination, a crank-case formed of sections provided with aligned transverse walls, said walls having complementary arcuate openings forming a cylindrical bearing-seat, a crank-shaft, a bearing for the shaft removably held in said seat and longitudinally movable on the shaft to permit it to be slipped into and out of the seat, and a seal-ring, rotatable with the shaft, having a side pressed against one end of the bearing units and removable through said seat when the bearing is removed.

19. In combination, a crank-case formed of sections and provided with aligned transverse walls, said walls having complementary arcuate openings forming a cylindrical bearing-seat, a crank-shaft, a bearing for the crank-shaft comprising a pair of complementary units fitting around the shaft and in the bearing seat and longitudinally movable on the shaft to permit them to be slipped into and out of the seat, one unit of each pair being rotatable around the shaft and in the seat to permit it to be turned out of the seat and removed when its complementary unit has been removed, and a seal-ring rotatable with the shaft and having a side pressed against one end of the bearing-units.

Signed at Chicago, Illinois, this 30th day of July, 1926.
